(57) **CLAIM**

We claim the ornamental design for a display panel with a computer-generated icon, as shown and described.

DESCRIPTION

FIG. 1 is a front view of a display panel with a computer-generated icon showing an embodiment of my new design; and,

FIG. 2 is a front view of the same embodiment, shown in a different environment.

The broken line showing of the display screen and portions of the graphical user interface, including the dot in FIG. 2, are included for the purpose of illustrating environmental structure and portions of the article and form no part of the claimed design.
